C. C. REYNOLDS.
SUPPORT OR STAND.
APPLICATION FILED MAY 29, 1916.

1,231,197.

Patented June 26, 1917.

UNITED STATES PATENT OFFICE.

CLINTON C. REYNOLDS, OF LE ROY, ILLINOIS.

SUPPORT OR STAND.

1,231,197.

Specification of Letters Patent. Patented June 26, 1917.

Application filed May 29, 1916. Serial No. 100,437.

To all whom it may concern:

Be it known that I, CLINTON C. REYNOLDS, a citizen of the United States, a resident of Le Roy, in the county of McLean and State 5 of Illinois, have invented new and useful Improvements in Supports or Stands, of which the following is a specification.

My invention relates to improvements in stands or supports and is particularly directed to a supporting stand for a barrel, can or similar receptacle, whereby the same may be securely held in a slightly elevated position and readily tilted for totally or partially emptying its contents or for refilling.

15 A further object is the provision of such a stand from which the barrel, can or other receptacle may be readily removed.

A further object is the provision of such a device whereby the receptacle may be readily 20 tilted and readily returned to its normal position.

Further objects include improvements in details of construction and arrangement whereby a simple and efficiently operating 25 device of this character is provided, capable of supporting and handling receptacles of various sizes and shapes and for containing the various liquids or fluids.

To the accomplishment of the foregoing 30 and such other objects as may hereinafter appear, my invention consists in the combination, construction and arrangement of parts hereinafter described and then sought to be defined in the appended claims, reference being had to the accompanying drawings forming a part hereof, and which show merely for the purpose of illustrative disclosure, a preferred embodiment of my invention, it being understood that various 35 changes may be made in practice within the scope of the claims without digressing from my inventive idea.

In the drawing,

40 Figure 1 represents a side elevation of a device constructed according to my invention, supporting a barrel, the complete tilted position being indicated in dotted lines;

Fig. 2 is a rear elevational view of the device, shown in Fig. 1, the barrel being completely tilted.

Referring now to the drawings, the numeral 1 designates the base of the device which as shown, is constructed of pipe, though any other suitable material may be used. It includes the horizontally extended side members 2 connected by the transverse

member 3 and having the vertical members 4 extending upwardly therefrom, the ends of which are provided with the elbow 5 to provide a horizontal pivot 6 on which the 60 barrel, can or other receptacle is pivoted.

The barrel, can or other receptacle is held in a frame work 7, which includes the flat bar or strap members 8 which extend across the bottom thereof and up along the sides as 65 at 9, having the outwardly turned flange 10 adapted to receive the threaded end 11 of the adjusting hook 12 which fits over the end of the barrel, can or other receptacle, and has the nut 13 secured on the screw 70 threaded portion 11 for adjusting purposes. The bar or strap member 8' extends at right angles to the bar or strap member 8 and is divided as at 13' so as to permit the ready removal of the barrel, can or other receptacle, having the securing plate 14 pivoted to one end as at 15, and having the bolt and nut connection 16 on the other side of the 75 line of division. When it is desired to remove the barrel, can or other receptacle, it 80 is only necessary to loosen the hooks 12 and remove the bolt and nut connection 16 which releases the upwardly extending portion of the bar or strap member 8' so that the barrel, can or other receptacle may be readily 85 removed therefrom in a lateral direction.

Means is provided for locking the barrel, can or other receptacle when in its completely tilted position and also to assist in supporting the same and returning it to its 90 normal position, including the pair of arms 17 which are pivoted on the transverse member 3, as at 18, and connected together by the transverse member 19. Links 20 are pivotally connected to the upper ends of 95 arms 17 as at 21 and are also pivotally connected at their other ends to the lower portions of the upwardly extending parts 9 of the strap or bar members 8, as at 22. At the rear ends, these links are provided with 100 the stop 23 in the form of a hook adapted to engage the vertical member 4 of the frame when the barrel, can or other receptacle is in its vertical position, and at its other end has the overlapping flange member 24 which 105 is adapted to engage the upper edge of the arm 17 when the barrel, can or other receptacle is in its completely tilted position, the pivots being arranged so that a lock is formed between these parts.

110 In use, a barrel, can or other receptacle may be readily inserted and supported by

the frame work, the pivot 6 extending through the vertical portions 9 of one of the bar or strap members 8. When it is desired to partially empty the barrel, can or other receptacle, it may be readily tilted to the desired degree, the parts being arranged so that it is counter-balanced to permit ready movement or it may be completely tilted if that be necessary and held in that position 10 by means of the locking construction specified. In this position, it may also be readily filled through the usual bung-hole. It is only necessary to break the joint or else to give the bottom end of the barrel, can, or 15 other receptacle, a fairly sharp blow to cause it to return to its normal vertical position.

The device operates therefore simply, and efficiently for the desired purpose, and is capable of a variety of uses where it is desired to maintain a supply of liquid and to dispense the same in small quantities from time to time.

What I claim is:—

1. A device of the character described including in combination, a base having spaced upright members, a supporting frame work for holding a barrel or other receptacle pivotally connected between said upright members, said frame work including strap members adapted to extend across the bottom of the receptacle and up along the sides thereof, one of said strap members being divided and having removable means for securing it together, and hook members adjustably secured to said strap members and adapted to engage the top of the receptacle.

2. A device of the character described including in combination, a base having spaced upright members, a frame work for holding a receptacle pivotally connected to said upright members, arms pivotally connected to said base and link members pivotally connected to said arms and to said frame work below its pivotal connection to the upright members.

3. A device of the character described including in combination, a base having spaced upright members, a frame work for holding a receptacle pivotally connected to said upright members, arms pivotally connected to said base and link members pivotally connected to said arms and to said frame work below the pivotal connection of the upright members, and stops on said links adapted to engage said arms when in a fully extended position to lock the parts in said extended position.

4. A device of the character described including in combination, a base having spaced upright members, a frame work for holding a receptacle pivotally connected to said up-

right members, arms pivotally connected to said base and link members pivotally connected to said arms and to said frame work below the pivotal connection of the upright members, a stop on each link adapted to engage said arms when in a fully extended position to lock the parts in said extended position, and a stop on the other end of each link to engage said spaced upright members to stop the receptacle in its normal position on its return movement.

5. A device of the character described, including in combination, a base having spaced upright members, a frame work for holding a receptacle, including strap members adapted to extend along the bottom thereof and up along the sides with hook members adjustably secured to the ends of said strap members and adapted to engage the top of the receptacle, arms pivotally connected to said base and link members pivotally connected to said arms and to said strap members at a point near the bottom of the receptacle, said strap members also having a pivotal connection with said spaced upright members adjacent the intermediate point of the receptacle.

6. In a device of the character described, including in combination, a base having spaced upright members, a frame work adapted to hold a receptacle mounted between and pivotally connected at an intermediate point to said spaced upright members, spaced arms pivotally connected to said base and a link pivotally connected to each arm and one side of said frame work below the pivotal connection of said spaced upright members with said frame work, a stop on the upper end of each link adapted to engage one of said spaced upright members when the receptacle is in an upright position, and another stop on each link adapted to engage said arm when the receptacle is in a horizontal position.

7. A device of the character described, including in combination, a base having a pair of spaced upright members and also a transverse member extending thereacross, a frame work for removably holding a receptacle and having a pivotal connection between said spaced upright members at an intermediate point, a pair of arms pivotally mounted on said transverse member of the frame work and connected together to move in unison, a link member pivotally connected to each arm and to the sides of said frame work at a point below the pivotal connection of the frame work with said spaced upright members.

CLINTON C. REYNOLDS.
